DISH OR SIMILAR ARTICLE OF HOLLOW WARE

Roger L. Nowak, West Boylston, Mass., assignor to Van Brode Milling Co., Inc., Clinton, Mass., a corporation of Massachusetts

Application May 20, 1955, Serial No. 36,131

Term of patent 7 years

(Cl. D44—15)

Fig. 1

Fig. 3

Fig. 1 is a front elevation of a dish or similar article of hollow ware, showing my new design;

Fig. 2 is a side elevation of the same; and

Fig. 3 is a bottom plan view thereof.

I claim:

The ornamental design for a dish or similar article of hollow ware, as shown.
